ADJUSTABLE STOP MEANS

Glenn E. Specht, Charlestown, W. Va., assignor to Pew-
hatan Brass & Iron Works, Ranson, W. Va., a corpora-
tion of West Virginia

Filed June 15, 1962, Ser. No. 202,784

4 Claims. (Cl. 251—285)

This invention relates generally to a combination angle and pressure reducing valve, and more specifically relates to such a valve which may be utilized in fire prevention systems for controlling water pressure to an outlet. The valve is particularly adaptable for use with water supply systems in which minimum pressures are desired at various levels. Valves of the type described are inserted at various levels so that fluid flow at the lower levels will not exceed limits which would reduce the required pressures at the upper levels.

An objective of this invention is to provide a reducing valve of the type described with an adjustable stop means which is simple and efficient in operation, and sturdy in construction.

A further objective of the invention is to provide a valve of the pressure reducing type which includes adjusting structure for preventing maximum flow during normal use, which is fully enclosed within the valve housing and thereby rendered tamper proof.

A further objective of the invention is to provide an adjustable pressure reducing valve that includes mechanism for permitting a selected amount of fluid flow therethrough in normal operation, and further structure including a frangible element which, when broken, permits the valve to be fully opened.

Another important objective of the invention is to provide an adjustable pressure reducing valve in which a lock mechanism is connected to the valve housing by a breakable link, and the release procedure is independent of the operation of the valve hand wheel.

A still further objective of the invention is to provide a novel valve housing which slidably receives a control rod which is locked in position by a lock assembly extending through the side wall of the housing.

These and other important objectives and advantages of the invention will hereinafter become more fully apparent from the following description of the drawings, illustrating a presently preferred embodiment thereof, and wherein:

FIGURE 1 is a side elevation view with portions broken away; and

FIGURE 2 is a side elevation with parts broken away showing a portion of the interior of the housing.

Referring now to the drawings wherein like numerals indicate like elements, the valve housing is indicated by the numeral 10. The housing is comprised generally of a body portion 12, a bonnet 14, and a cap 16. The body 12 defines a fluid path or chamber 18 between an inlet 20 and an outlet 22. The inlet is attached to a standpipe or the like, and the outlet is led to a desired point of use.

A valve seat 24 within chamber 18 is adapted to be closed and opened by a conventional disc-like closure member 26. The closure member includes a conventional packing gland 27 which, when forced against the valve seat, interrupts fluid flow therethrough. The closure member 26 has a threaded spindle receiving bore 25 about its upper surface. A turn spindle 28 having a lower flange 31 is secured within the bore via a threaded spindle lock nut 32 mating with the interior threads of the bore. The lock 32 secures the flange 31 between its skirt section and bottom of the bore. Lock nut 32 includes an outwardly extending upper flange 36 for purposes hereinafter described.

Threads 38 are formed in spindle 28 along most of its longitudinal length. The spindle extends through bon-

2

net 14 and cap 16 where it is terminated by a conventional hand wheel 40. The upper portion of the spindle is suitably secured to the cap by a conventional packing gland and stuff nut, generally indicated by the numeral 42. The bonnet 14 is secured to the body 12 by a bonnet nut 44 and the cap 16 is secured to the upper end of the bonnet by a cap nut 46.

An adjustable stop collar 50 is threadably received about the spindle 28. As best seen in FIGURE 2, the bonnet 14 is counterbored at 52 and is equipped with a central threaded bore 54 which receives the spindle 28. Between threaded bore 54 and the counter bore 52, a ledge 56 is defined. As will be readily understood by those skilled in the art, closure member 26 is moved toward and away from its seat 24 via a rotation of hand wheel 40. The degree of pressure drop across the valve depends on the distance between the valve seat and the closure member.

Bonnet 14 is provided with an offset passageway 58 which communicates counter bore 52 with chamber 18. Disposed within this passageway is a control rod 60 which is serrated or grooved about its length, as indicated by the numeral 64. Referring back to FIGURE 1, it can be seen that rod 60 is so guided by passageway 58 that it is capable of limited sliding movement between the top of flange 36 and the bottom of the adjustable stop collar 50.

A cross bore 66, threaded at 67, through the side wall of bonnet 14 threadably receives a locking spindle 68 therethrough which is equipped with a lock handle 70 at its outer end and a lock pad 72 at its inner end. The cross bore 66 extends into the passageway 58 and thus provides a means whereby the lock pad may be urged against the control rod 60 as handle 70 is rotated. The concave inner face 71 of pad 72 is serrated or grooved to mate with the grooves 64 of rod 60.

The bonnet 14 is provided with a lug extension 74 which is spaced from, and immediately above, the handle 70. The lug 74 and handle 70 are adapted to receive therebetween a conventional breakable link 78 which may be made of zinc or the like. Spaced below the lock pad 72, but offset from cross bore 66, is a threaded aperture 80, from which a boss 82 threadably extends. The boss is counter bored at 84 and receives a spring and ball assembly 96 therein. The spring and ball arrangement against the grooves 64 provides a loose braking action for positioning rod 60.

In order to pre-set the valve for desired flow, the handle 70 is rotated counterclockwise until the pad 72 disengages the rod 60. The hand wheel 40 is rotated until the valve is wide open. As the valve is opened, the collar 50 of course moves upwardly therewith. Cap nut 46 is loosened and cap 16 is raised until the cap strikes the hand wheel. An operator then has access to the interior of the housing. Control rod 60 is pushed downwardly and set screws 88 are loosened and adjustable stop collar 50 is rotated until it strikes the top of control rod 60. This is a zero setting. The adjustable stop collar is then rotated counterclockwise upwardly until the indicia 90 are properly aligned with corresponding score line indicia 91 on lands of threads 45. Of course, any type of indicia or scale suitable for disclosing the relationship between collar 50 and the remaining elements would be satisfactory. The set screws are tightened so as to lock the adjustable stop collar to the spindle at the selected position. The bonnet cap is moved downwardly and the nut 46 is tightened to secure the assembly. Hand wheel 40 is then rotated until the closure member 26 firmly engages its seat 24. As the shaft 28 and adjustable collar 50 move downwardly, the rod 60 is moved downwardly therewith after contact with collar 50. Since the adjustable stop collar 50 was adjusted upwardly, it will have some downward movement prior to making contact

with the rod 60 and the extent of this movement will be determinative of the permitted valve opening. After the valve is seated there is a certain distance between the bottom of rod 60 and the surface 32 in which the valve can freely move under the control of handle 40. The handle 70 is rotated clockwise until the serrations in pad 72 firmly engage the serrations 64. The breakable link 78 is secured between the handle 70 and the lug 74. A positioning screw 92 is tightened and the valve is now ready for installation with all adjustments fully enclosed and tamper proof.

In normal operation the valve can now be opened until the flange 32 strikes the bottom of rod 60. Only a great amount of torque pressure applied to handle 40 will permit the valve to be opened any farther. However, in the event of an emergency, the frangible element 78 can be broken and pad 72 moved out of engagement with rod 60. The valve may now be opened to its fullest extent, as flange 32, rod 60, and collar 50 move upwardly in unison. After the emergency has passed, the valve is reset by merely turning hand wheel 40 clockwise until the closure member 26 is seated. Handle 70 is again rotated clockwise until the pad engages the serrations 64. A new frangible element 78 is applied and the valve is again ready for normal use.

In a general manner, while there has been disclosed in the above description, what is deemed to be the most practical and efficient embodiment of the invention, it should be well understood that the invention is not limited to such an embodiment as there might be changes made in the arrangement, disposition and form of the parts without departing from the principle of the present invention as comprehended within the scope of the accompanying claims.

I claim:

1. A valve comprising a housing having a fluid path between an inlet and an outlet, a valve seat formed in said path, a closure member complementary with said seat, a spindle attached to said closure member, said housing having a first interior opening threadably receiving said spindle and a second interior opening having a central axis parallel with the central axis of said first opening, means to reciprocate said spindle along its longitudinal axis, a stop collar adjustable along the length of said spindle, a rod having an irregular surface along its length slidably received in said second opening and movable between said stop collar and the top of said closure member, a lock pad having an inner irregular surface disposed within said housing, and means supported by said housing moving said pad into and out of engagement with said rod.

2. In a reducing valve, a housing having a fluid path therethrough, a seat defined along the length of said path, a rotatable and longitudinally movable spindle, a closure

member attached to said spindle, and a hand wheel attached to the other end of said spindle whereby the closure member is movable toward and away from said seat upon a rotation of said handle; that improvement comprising a stop threadably received about said rod for adjustable movement along the length of said spindle, a rod parallel to said spindle slidably received in said housing and movable along a path substantially parallel to the longitudinal axis of said spindle, between said seat and said stop, said housing having an aperture therethrough leading to a point intermediate the length of said rod, a rod-engaging member threadably received in said aperture, a handle for screwing said member toward and away from engagement with said rod, and breakable link means between said handle and said housing.

3. In a reducing valve, a housing having a fluid path therethrough, a seat defined along the length of said path, a rotatable and longitudinally movable spindle, a closure member attached to said spindle, and a hand wheel attached to the other end of said spindle whereby the closure member is movable toward and away from said seat upon a rotation of said handle; that improvement comprising a collar adjustable along the length of said spindle, a rod parallel to said spindle slidably received in said housing and movable along its longitudinal axis, between said seat and said collar, a lock rod extending through said housing at an angle substantially perpendicular with said rod, a handle on the outside of said housing for moving said lock arm into and out of engagement with said rod, an exterior flange on said housing closely adjacent said handle, and breakable link means between said flange and said handle.

4. The valve described in claim 3 wherein a braking assembly supported by said housing is in constant engagement with said rod and is of sufficient strength to hold said rod at its position of rest when said lock arm is out of engagement with said rod and said braking assembly is of sufficient looseness to permit movement of said rod when engaged by said closure member or said adjustable stop collar.
